UNITED STATES PATENT OFFICE.

EZECHIEL WEINTRAUB, OF LYNN, MASSACHUSETTS, ASSIGNGR TO GENERAL ELECTRIC COMPANY, A CORPORATION OF NEW YORK.

INCANDESCENT LAMP.

1,049,786.

Specification of Letters Patent.

Patented Jan. 7, 1913.

Application filed October 2, 1908. Serial No. 455,885.

To all whom it may concern:

Be it known that I, EZECHIEL WEINTRAUB, a citizen of the United States, residing at Lynn, county of Essex, State of Massachusetts, have invented certain new and useful Improvements in Incandescent Lamps, of which the following is a specification.

My present invention relates to incandescent lamps, and more particularly to lamps in which the incandescing member or filament is normally surrounded by a vaporized metal.

According to my invention the filament is so proportioned and disposed as to insure a long life and good efficiency, and with freedom from danger of short circuits in the lamp because of the presence of the mercury or other metallic vapor.

In the accompanying drawing, Figure 1 is an elevation of the completed lamp with certain portions broken away, and Fig. 2 is a detail.

The lamp shown in Fig. 1 comprises an ordinary screw socket 1 to which is attached a protective or inclosing globe 2 normally communicating with the atmosphere through an opening 3 at the point where most lamp bulbs are sealed off. Within this inclosing globe is an evacuated U-shaped tube 4 through which extends a filament 5 supplied with current through the usual leading in conductors 6 and 7. Sufficient mercury is introduced into this evacuated tube 4 to provide an appreciable quantity of mercury vapor therein when the filament 5 is at normal running temperature. When the lamp is cold this mercury condenses and forms a globule of about the size indicated at 8 in the drawing.

I have found that if the filament 5 is of uniform cross section throughout its length, there is a tendency for the formation of a mercury arc shunting the lower or curved portion of the filament loop. When such an

arc forms, it has as cathode, a spot on the 45 filament at or adjacent to the curved portion. The maintenance of such an arc in shunt to a portion of the filament and with its cathode on the filament is detrimental and even destructive to the lamp. 50

According to my present invention I make the filament 5 of such conductivity throughout the curved portion that it runs much cooler, and so is protected against the possibility of a mercury arc between adjacent portions. This increased conductivity may be secured by making the curved portion of the filament out of material of higher conductivity than that of the legs of the filament. 55 Or it may be secured by increasing the cross section throughout the curved portion 9, as by splicing in a section of heavy filament or by locally "flashing" to secure a corresponding increase in diameter.

An embodiment of my invention is indicated somewhat diagrammatically by the drawings, where the curved portion 9 of the filament is shown as of higher conductivity than the straight portions and therefore operative at a lower temperature. 65

What I claim as new and desire to secure by Letters Patent of the United States, is:

In an incandescent lamp, the combination of a U-shaped tube, mercury therein which is more or less vaporized during operation 75 of the lamp, and a bent filament within said tube, conforming to the shape of said tube, the bent portion of the filament being thicker and of greater conductivity than the leg portions thereof to prevent disintegration of the 80 filament at the bend.

In witness whereof, I have hereunto set my hand this thirtieth day of Sept., 1908.

EZECHIEL WEINTRAUB.
